ACCORDION GRILL

Vincent Castiglione, Detroit, Mich.

Application May 11, 1953, Serial No. 24,953

Term of patent 7 years

(Cl. D56—1)

To all whom it may concern:

Be it known that I, Vincent Castiglione, a citizen of the United States, residing at Detroit, in the county of Wayne and State of Michigan, have invented a new, original, and ornamental Design for an Accordion Grill, of which the following is a specification, reference being had to the accompanying drawing, forming part thereof.

I claim:

The ornamental design for an accordion grill, as shown and described.

VINCENT CASTIGLIONE.
